HYDRAULIC OPERATOR

David R. Hillis, Detroit, Mich., assignor, by
mesne assignments, to Reconstruction Finance
Corporation, Detroit, Mich., a corporation of
the United States

Application December 2, 1936, Serial No. 113,873

13 Claims. (Cl. 121—157)

My invention pertains to fluid pressure motors and more particularly to a hydraulic operator for actuating parts of machinery, valves, pumps and the like.

5 It is an object of my invention to provide a rugged, compact, hydraulic operator of positive operating characteristics, which can be made of simplified construction and few moving parts.

It is also an object of my invention to provide a 10 hydraulic operator comprising a casing having an inlet and an outlet port, a fluid pressure responsive operator member movably disposed in the casing for movement by high pressure fluid applied in the inlet port to generate working power, and fluid responsive valve means for controlling the application of the pressure fluid from the inlet port to reversely move the operator member.

It is a further object of my invention to provide 15 such a hydraulic operator having fluid conducting means controlled by the movements of the working operator for applying fluid pressure from the inlet port to reversely move the fluid responsive valve.

20 Another object of my invention is to provide a hydraulic operator of the above type having interlocking means actuated by the movements of the operator member for interlocking with and controlling the movements of the said fluid pressure responsive valve.

25 Another object of my invention is the provision of such a hydraulic operator wherein the working operator member is a hollow piston or sleeve having its fluid pressure controlling valve 30 slidably carried therein for establishing fluid conducting connections to reversely move the hollow piston, fluid conducting ports and passages controlled by the hollow piston to apply fluid pressures for reversely moving the valve, an interlocking pin slidably disposed in the hollow piston 35 for engaging at one end with either one of two interlocking recesses in the valve and at its other end engaging suitable camming surfaces in the casing for locking the fluid responsive valve in either one of two extreme positions during pre-40 determined movements of the hollow operator piston.

45 Another object of my invention is to provide a hydraulic operator comprising, a fluid pressure responsive piston, a fluid responsive valve for applying fluid pressure to reversely operate the piston, and a piston driven valve for applying fluid pressures to reversely move the fluid responsive valve.

50 Also it is an object of my invention to provide

a hydraulic operator of the above type wherein the piston actuated valve is actuated through slack motion driving means interconnected from the piston, and interlocking means is actuated by movement of the piston driven valve and of the other valve in response to the applied fluid pressures whereby simultaneous shifting of the valves is prevented.

5 The novel features that I consider characteristic of my invention are set forth with particularity in the appended claims. The invention itself, however, both as to its construction and its method of operation, together with additional objects and advantages thereof, will best be understood from the following descriptions of specific embodiments, when read in connection with the accompanying drawings, in which:

Fig. 1 is a side elevational view of my hydraulic operator;

Fig. 2 is a longitudinal sectional view taken on line 2—2 therethrough to show the co-operative relation of the movable parts disposed therein;

Fig. 3 is a similar view showing the movable elements of the device in different positions;

Fig. 4 and 5 are cross-sectional views taken 25 on section lines 4—4 and lines 5—5 respectively as shown in Fig. 3;

Fig. 6 is a side elevational view showing another embodiment of my hydraulic operator;

Fig. 7 and 8 are transverse sectional views 30 thereof taken on section lines 7—7 and 8—8 respectively as shown in Fig. 6;

Fig. 9 is a longitudinal sectional view taken therethrough on line 9—9 as shown in Fig. 7;

Fig. 10 is a longitudinal sectional view taken 35 therethrough on line 10—10 as shown in Fig. 8; and

Fig. 11 is a similar view showing the movable valves disposed in their alternative operative positions therein.

40 Referring more specifically to Figs. 1—5 of the drawings, I have illustratively disclosed an embodiment of my improved hydraulic operator comprising a housing or casing 1, which may be a casting of any suitable metal. The casing is 45 provided with an inlet port 3 for receiving any working medium or fluid from any source, or uniflow system, which provides a supply of the working fluid under suitable pressure conditions. An outlet port 5 is also provided in the casing 50 for discharging the working fluid, which may return into a reservoir, if the device is used in a continuous circuit system. The ports 3 and 5 are passages provided by drilling into the casting 1 axially, and preferably from opposite ends, to 55

facilitate connection of the hydraulic operator into a system, for which purpose each port is provided with internal threads 7.

To generate power for useful work, a fluid pressure responsive operator member, comprising a hollow piston 9, is slidably disposed in a cylindrical aperture 11 which extends axially through the casing. The piston guiding aperture 11 is provided by boring axially through the casing, and the opposite ends are internally threaded to receive fluid flow restricting heads or plugs 13 and 15. The cylinder head plugs are provided at the outer ends with laterally projecting shoulders 17 which are of hexagonal, or other suitable form, for receiving a wrench for turning the plugs into the casing firmly for sealing the ends of the bore. Also the plugs 13 and 17 extend suitably into the cylindrical bore 11 for properly limiting the extreme positions of the hollow piston 9 therein.

20 The operator piston 9 may be formed by turning a piece of metal of suitable cylindrical dimensions and boring the same axially, or a tubular sleeve may be utilized, and internal threads are provided at opposite ends of the piston to threadably receive plugs 13 and 17 therein. Each of the piston plugs 13 and 17 comprises a laterally extended hexagonal head 23 on the outer end for operatively receiving a wrench.

For applying the high pressure working fluid 30 from the inlet aperture 3 to reversely move the operator piston 9, I provide a plurality of spaced inlet ports 25 and 27 connecting from the inlet aperture 3 through the side walls of the piston guiding bore 11 adjacent opposite ends thereof. 35 A third inlet port 29 connects from the inlet passage 3 through the side walls of the piston guiding bore 11 at a point substantially in the middle thereof. The port apertures 25, 27 and 29 may be provided by drilling through from the outer surface of the casing 1 and thereafter closing the portion of each bore, which extends from the inlet passage 3 to the outer surface of the casing, by a metallic plug secured therein as by threading or welding in any suitable manner, as 40 will be readily understood.

The hollow operator piston 9 is provided with ports 31, 33 and 35 which pierce the side walls thereof for operatively connecting with proper ones of the stationary ports 25, 29 and 27 in the casing as the piston slides therein. For this purpose, the end piston ports 31 and 35 connect selectively with the stationary ports 25 and 27 as the piston moves to one end or the other in the casing. In the outer surface of the piston 9 a groove 39 is cut axially connecting into the central piston port 33 to provide continuous connection from the central inlet port 29 in the casing as the piston slides to and fro.

For controlling the flow of working fluid into and through the hollow piston sleeve 9, I provide a piston valve 41 of the dumb-bell type slidably disposed therein. The piston valve comprises fluid flow restricting valve heads 43, 45, 47 and 49 which slide snugly in close fitting relation in the bore 51 of the hollow piston 9. The flow restricting heads of the slidable valve 41 are connected in spaced relation by connecting rods 53, 55 and 57 of reduced cross-section whereby fluid can flow freely between them. The intermediate 60 portion of the central connecting rod 55 is enlarged to provide interlocking recesses 59 and 61 at opposite ends thereof, but its diameter is less than that of the bore 51 so that fluid can pass freely around it. The end heads 43 and 49 of the 65 sliding valve 41 carry outwardly projecting

stops 63' which serve to abut the inner ends of the plugs 13 or 17 to accurately determine the end positions of the valve, in proper relation to the ports connecting through the side walls of the piston sleeve 9, and to avoid obstruction of 5 the end ports therein.

The movement of the sliding valve 41 in the hollow piston 9 is controlled by fluid pressures applied on the ends of the valve, and also by an interlock which prevents simultaneous shifting of 10 the hollow operator piston and of the sliding valve in response to the fluid pressures applied thereon. For this purpose an interlocking pin 63 is provided which is slidably disposed in a suitable aperture and in order to accommodate it, two spaced camming recesses 65 and 67 are provided in the cylindrical bore of the casing at points diametrically opposite port 33 in each of its extreme positions.

20 Thus, when the valve 41 starts to move, the enlargement 55 will force the pin 63 upwardly into one of the camming surfaces 65 or 67 to prevent movement of the hollow piston 9 at the same time and conversely when the parts are in 25 proper position for the shifting of the hollow piston 9, the movement of said piston will cause the camming surfaces 65 or 67 to force the pin 63 downwardly into the proper interlocking recess 59 or 61 in the valve 41, thus preventing it 30 from shifting at the same time. The ends of the interlocking pin are rounded for smooth engagement in the respective recesses.

Additional ports 69 and 71 are provided, piercing the side walls of the slidable operator piston 35 sleeve 9, adjacent the ends thereof, at points spaced correspondingly to the end piston ports 31 and 35 previously described. A pair of intermediate spaced ports 73 and 75 are provided in the side walls of the piston 9 and grooves 77 40 and 79 are provided in the outer surface of the piston extending axially from their outer ends for continuous connection with stationary ports 81 and 83 respectively which are provided in the casing for connecting into the outlet passage 5. 45 Also connecting from the outlet passage 5 in the casing are ports 85 and 87 which pierce the side walls of the piston guiding bore 11 at points suitably spaced for connecting selectively with either end port 69 or 71 in the piston 9.

50 For providing additional fluid discharging connections, the piston ports 69, and 73 with groove 77 may be so spaced that when the piston 9 is moved toward the casing ports 85 and 81 they are both connected with the piston port 73, as shown 55 in Fig. 2. Likewise casing ports 83 and 87 are similarly spaced in relation to the piston port 75 and its connecting groove 79.

Working fluid for slidably operating the piston 9 is discharged through the piston 9 by the 60 slidable valve 41 therein. For applying an operating pressure on one end of the piston 9, the sleeve thereof is provided with a passage 88 drilled from said end axially therein, as represented by dotted lines, to a point slightly beyond the center and thence connected through a radial portion which opens into the hollow piston and comprises a valve controlled port 90. Similarly, for discharging fluid to apply an operating pressure upon the opposite end of the piston 9 a passage 70 65 92 is drilled axially therein and connects into the piston through a valve controlled port 94.

75 For guiding the slidable operator piston 9 and preventing rotation of the piston, a guide pin 99 projects from one side into which it may be 75

secured by threading, or in any other suitable manner. The outer end of the guide pin 68 projects into a guide groove 31, of suitable conformation, cut axially at a suitable position in the side walls of the piston guiding bore 11. Rotation of the piston being thus prevented, the operative connection of the piston ports with the proper casing ports is provided, and the outer end of the interlocking pin 63 is properly engaged by the camming recesses 65 and 67 in the casing as the piston reciprocates.

For operatively connecting the slideable operator piston 9 with any mechanical device to be thereby actuated, a piston rod, or operator rod, 93 is secured at its inner end to one of the piston plugs 21 in any suitable manner, as by welding or threading thereto. The operator rod 93 extends from the casing through one of the cylinder head plugs 15 which is suitably apertured. The outer portion of the aperture in the head plug 15 is counter-bored to a larger diameter to provide a packing gland 95 to receive packing 96 which is compressed around the slideable operator rod 93 by a packing nut 97 threadably received therein. For installation, the hydraulic-operator casing may be clamped, or mounted in any suitable manner, or screw receiving pedestal portions may be conveniently provided, as will be understood.

In operation, assuming the parts as shown in Fig. 2, the high pressure working fluid enters the inlet passage 3. Pressure applied through ports 25 and 31 into the hollow piston now tends only to hold the fluid responsive slide valve 41 to its right hand position, as shown, the pressure having previously shifted said valve. From inlet passage 3 fluid flows through ports 29 and 33 into the hollow piston, thence around the reduced connecting portion 55 at the middle of the valve 40 and by way of port 90 and passage 88 into the space at the left hand end of the piston.

The pressure thus admitted moves the hollow piston to the right, and its initial movement cams the interlocking pin 63 down to hold the valve 41. The groove 39 provides continuous connection of the inlet port 3 through the port 29 with the port 33 in all positions of the piston and the fluid pressure is continuously applied in the middle of the piston. Hence fluid continues to flow, as traced above, and the piston is moved to its extreme right hand position abutting the head plug 15, as shown in Fig. 3, but the valve 41 will still be in its right hand position.

As the port 25 is now closed, fluid will pass through ports 27 and 35 into the hollow piston and shift valve 41 to the left, as shown in Fig. 3, its first movement causing the interlocking pin 63 to be raised so that its outer end is received in camming recess 67, thus preventing it from shifting at the same time. This is not so important during operation of the parts, but very important when the pressure has been discontinued and is then reapplied, as it prevents the parts from stopping on dead center.

The movement of the valve 41 to its left-hand position completed the connections for applying the pressure of the working fluid to the right hand end of the piston which will be thereby returned to its left hand position. For this operation the fluid flows from the inlet passage 3 by way of ports 29, and 33, through the hollow piston around the restricted middle portion 55 of the valve 41, thence by way of port 94 and passage 92 into the space at the right hand end of the piston. As the piston begins to move, its

initial movement depresses the interlocking pin 63 thus holding the valve 41 till the movement is completed. During this operation the axial groove 39 provides continuous connection between the ports 29 and 33. The movement of the piston 9 completed to the left, the outer end of the pin 63 enters recess 65 in the casing being raised by the initial movement of the valve 41 in the reverse direction.

The above cycle of operations is repeated successively, so long as working fluid of a suitable pressure is supplied to the inlet port 3, and the operator rod 93 is thus reciprocated by the piston for actuating any pump, valve, or other mechanically movable element which is to be controlled thereby.

In accordance with another embodiment of my invention, as shown in Figs. 6-11, a casing 101 is provided with a large aperture or piston guiding bore 103 extending therethrough and smaller, valve receiving, apertures 105 and 107 drilled therethrough, in spaced relation and preferably parallel thereto to provide a unit which is compact and conveniently connectable. The casing 101 is preferably a suitable casting comprising an elongated base 102, integral therewith. The base 102 is provided with a pedestal portion 104 upon which my hydraulic operator may be mounted in any desired location.

In this embodiment of my hydraulic operator, the movable operator member for translating the pressure of the working fluid into mechanical motion for doing useful work comprises a piston 109 slidably disposed in the piston guiding bore 103. The operator piston 109 comprises a substantially cylindrical body of a suitable diameter for sliding freely in the cylindrical aperture 103, and it is provided with a piston rod, or operating shaft 111, which is connected, as by threading or welding, to one end thereof. The piston rod 111 projects for connection with any mechanical element to be actuated thereby. The ends of the piston guiding cylinder 103 are provided with internal threads for operatively receiving a cylinder head plug 113 in one end thereof comprising a laterally projected shoulder 115 which may be of hexagonal or other suitable conformation for receiving a wrench, by which it is conveniently installed or removed. In the other end of the piston guiding bore 103 a cylinder head plug 117 is threadably secured, which comprises an outwardly projecting sleeve 119 having an enlarged counter-bore 121 extended therein to provide a packing gland wherein packing material 122 is firmly compressed around the operator shaft 111 by means of a packing ring 123. For compressing the packing toward the rod 111 the inner end of the pack ring 123 is suitably tapered and a wide flange 125 is provided upon the outer end for engagement by a packing nut 127, which is internally threaded to be received upon external threads provided upon the packing sleeve 119.

A fluid responsive piston valve 129, is slidably disposed in the valve receiving aperture 107 for controlling the application of fluid pressures to reversely operate the working piston 109. The fluid responsive valve 129 is of the dumb-bell piston type and comprises flow restricting heads 131, 133, 135, and 137 joined together in spaced relation by connectors 139, 141 and 143, which are of reduced cross-section to permit the working fluid to flow freely around. The intermediate connector 141 is of larger diameter than the other connectors to provide interlocking recesses 145 and 147, which are disposed at the ends of

the connector adjacent the heads 133 and 135 respectively. The valve bore 107 is provided with internal threads adjacent the opposite ends thereof for receiving suitably threaded plugs 149, which are turned firmly therein to seal the ends of the aperture, and also to provide limiting stops for the valve. Projecting outwardly from the outer ends of the valve heads 131 and 131 are suitable stops 151 provided for abutting the adjacent plugs 149 to thereby limit the position of the slideable valve 129 in spaced relation from the ends of the bore 107.

The piston controlling valve 129 is in turn operated by fluid pressures applied alternately to the ends thereof, in accordance with the movements of a piston driven valve 153 which is slidably disposed in the aperture 105. The piston driven valve 153 comprises flow restricting heads 155, and 157, connected in spaced relation by a connector 159 of reduced cross section to provide for the free flow of fluid around it. At one end the head 153 is joined thru a connector 161, of reduced cross section, to the inner end of a valve rod 163. The valve actuating rod 163 projects outwardly from the end of the aperture 105 through a packing fixture 165 which comprises a suitable packing gland and nut for providing a slideable seal around the rod. From the valve head 155, at the opposite end of the valve, a reduced connector 167 is joined to the inner end of a rod 169 which projects from the opposite end of the bore 105 through a suitable packing fixture 171. Upon the outer end of the stop rod 169 an annular ring 173 may be firmly secured, in any suitable manner, as by threadable engagement thereon, by which the relative position of the connected valve may be readily ascertained when it is desired to adjust the adjustable stops hereafter to be described.

The valve rod 163 is provided with a pair of adjustable stops 175 and 177 secured in spaced relation thereon in any suitable manner. For driving the valve rod 163, the piston rod 111 is provided with an actuator 179 which is secured adjustably thereon as by a clamping bolt 181 on each side for drawing up a clamp 182. The upper portion of the actuator 179 extends upwardly from the piston rod adjacent the valve rod 163 between the stops 175 and 177 thereon. Thus as the piston rod is slidably operated by its piston, the actuator 179 alternatively engages the stops on the valve rod to throw the valve 153 to its alternative positions after any desired predetermined movement of the piston rod has been completed.

In its operation the piston driven valve 153 controls fluid conducting means for reversely operating fluid responsive valve 129, as will be subsequently set forth, and a mechanical interlock 60 is provided which prohibits both valves from shifting simultaneously. For this purpose, I provide a slideable interlocking pin 183, which is slidably disposed in an aperture 185, which extends directly between the center points of the valve apertures 105 and 107 in the casing. The interlocking pin 183 is provided with rounded ends which are thus disposed for operatively engaging recesses 187 and 189, which are provided in the driven valve 153 as well as the interlocking recesses 145 and 147 provided in the fluid responsive valve 129.

The pin is longer than the aperture 185 in which it is mounted. Hence, whenever one valve moves, it forces the adjacent end of the pin out 75 of its recess, causing it to project into the other

valve aperture, being received in one of the recesses of the other valve. Thus it is impossible for both valves to move simultaneously and the valves can never stop on dead center.

Working fluid enters the casing 101 under pressure from a suitable source such, as a pipe line 191, which is threadably connected into the outer end of an inlet port 193 and, as shown in Figs. 10 and 11, passes through a passage 195 into the valve bore 105, at substantially the middle thereof. Fluid pressure is thus continuously applied in the space between the valve heads 155 and 157 of the valve 153. The valve is arranged to reciprocate through a distance which is slightly less than the distance between the heads. From 15 the mid-point of the valve guiding bore 105, a passage 196 continuously connects, as shown in Figs. 8 and 9, into the mid-point of the valve guiding bore 107, whereby the line pressure is also continuously applied into the space between 20 the heads 133 and 135 of the fluid responsive valve 129.

From the centrally charged space in the driven valve 153, high pressure fluid is discharged through a passage 199, into the left hand end 25 of the valve guiding bore 107, as shown dotted in Fig. 10. Hence driving the valve 153 to the right tends also to move the fluid responsive valve 129 in the same direction. The passage 199 connects into the valve bore 105 at a point suitably disposed to the right of the center to be controlled by the valve head 157 for successive connection with inlet port pressures every time the driven valve 153 is moved to the right.

When the driven valve 153 moves to the left, 35 its head 155 uncovers the port of a passage 201, shown dotted in Figs. 10 and 11, which extends through the casing 101 and discharges fluid into the right hand end of the valve guiding bore 107 and the fluid responsive valve 129 is thus moved to the left, as shown in Fig. 11. The stops 151 on the ends of fluid responsive valve 129 serve to stop it in spaced relation from the end plugs 149 whereby the fluid can enter freely from either passage 199 or 201 to quickly throw the valve 129 to its alternative position.

The reciprocating motion thus imparted to the valve 129 discharges the high pressure working fluid from the space between the heads 133 and 135 alternatively through passages 203 or 205 into the respective right hand or left hand end of the piston guiding aperture 103, as shown in Fig. 9. The opening ports of the passages 203 and 205 are suitably disposed in bore 107 for control by the movements of the valve heads 133 and 135 respectively whereby movement of the fluid responsive valve 129 to the right, passes fluid through passage 205 to drive the piston 109 to the left, and vice versa.

The passages 203 and 205, connecting to the ends of the piston guiding bore 103, serve alternatively for intake and exhaust. As shown in Fig. 9, fluid is being discharged through passage 205 to move the piston 109 to the left. As this operation takes place, the fluid previously charged into the cylinder at the left of the piston 109 is now exhausted through passage 203 into valve bore 107, from which it passes through an exhaust passage 207, into an outlet port 209. The outer end of the outlet port 209 is threaded for 60 connection with a pipe 211 which discharges the exhaust fluid, as it returns to the line, if the hydraulic operator is used in a closed system. A corresponding exhaust passage 213 is interconnected between the valve receiving apertures 105 75

and 187 at a similar distance from the center. Equally spaced on the opposite side from the center, is an exhaust passage 215, connecting from the outlet 209 into the valve bore 187 for connection with the passage 208 to receive fluid exhausted by the return stroke of the piston.

5 Directly above the passage 215, is a passage 217, connecting the valve receiving apertures 185 and 187, corresponding to port 213. Thus, exhaust from the right of valve receiving aperture 187 returns through passage 208 into valve receiving aperture 185, as seen in Fig. 10, thence through passage 213, again through valve receiving aperture 187 between heads 131 and 133, 10 thence out through passages 207, 209 and 211. The reverse is self-evident.

15 As the piston 189 is thus operated from side to side it in turn drives the valve 129 through the slack motion connectors 176 and 177. The motion of the driven valve 129 from end to end of its bore 185 applies fluid pressures to opposite ends of the fluid responsive valve 128 through the fluid conducting connections thus established and thereafter releases the interlock. This in turn reciprocates the fluid responsive valve 128 in its bore to apply reverse operating fluid pressures from the inlet port 193 to in turn reversely operate the piston 189. Operating cycles comprising the above operations continue successively so long as suitable fluid pressures are applied in the inlet port 193.

20 It will be seen that I have provided a positive acting hydraulic operator of simple constructions and few moving parts.

25 Aside from the specific embodiments of the invention herein shown and described, it will be understood that numerous details of the construction may be altered or omitted without departing from the spirit and scope of the invention as disclosed and claimed, and that I do not desire to limit the invention to the exact constructions herein set forth.

I claim:

1. In a hydraulic operator for use in uniflow fluid pressure systems the combination of, a casing having an inlet port and an outlet port, a fluid pressure responsive operator member movably disposed in said casing, fluid responsive valve means movable in said casing for controlling the application of pressure fluid from the inlet port to reversely move said operator member, and an interlock actuated by the movements of said operator member for interlocking with and controlling the movements of said fluid responsive valve means.

2. In a hydraulic operator for use in uniflow fluid pressure systems the combination of, a casing having an inlet port and an outlet port, a fluid pressure responsive operator member movably disposed in said casing, fluid responsive valve means movable in said casing for controlling the application of pressure fluid from the inlet port to reversely move said operator member, fluid conducting means controlled by the movements of said operator member for applying fluid pressure from the inlet port to reversely move said fluid responsive valve means, and an interlock actuated by the movements of said operator member for interlocking with and controlling the movements of said fluid responsive valve means.

3. In a hydraulic operator for use in uniflow fluid pressure systems the combination of, a casing, a substantially cylindrical aperture in said casing, a fluid responsive operator member slid-

ably disposed in said aperture, an inlet port in said casing for receiving pressure fluid for moving said operator member, an outlet port in said casing for discharging fluid therefrom, a fluid responsive valve movable in said casing for controlling the application of fluid pressure from said inlet port into opposite ends of said recess to reversely move said operator member, fluid conducting means controlled by the movements of said operator member for applying fluid pressure from the inlet port to reversely move said valve, and an interlocking pin actuated by the movements of said slideable operator member for interlocking with and controlling the movements of said fluid responsive valve means.

4. In a hydraulic operator for use in uniflow fluid pressure systems the combination of, a casing, a substantially cylindrical aperture in said casing, a fluid responsive operator member slidably disposed in said aperture, an inlet port in said casing for receiving pressure fluid for moving said operator member, an outlet port in said casing for discharging fluid therefrom, a fluid responsive valve movable in said casing for controlling the application of fluid pressure from said inlet port into opposite ends of said recess to reversely move said operator member, fluid conducting means controlled by the movements of said operator member for applying fluid pressure from the inlet port to reversely move said valve, two interlocking recesses in said fluid responsive valve corresponding to its extreme positions, an interlocking pin slidably disposed to project one end thereof into either one of said interlocking recesses, and camming means controlled by the movements of the operating member for engaging the other end of said interlocking pin to interlock and control the movements of said valve in response to the fluid pressures applied thereto.

5. In a fluid pressure actuated operator the combination of, a casing having an inlet port and an outlet port, an aperture in said casing, a hollow operator piston slidably disposed in said aperture, fluid responsive valve means carried in said hollow piston for establishing fluid conducting connections to reversely move the hollow piston, fluid conducting ports and passages controlled by the hollow piston for applying fluid pressures to reversely move the valve therein, camming surfaces in said casing, and an interlocking member carried by said hollow piston to engage said camming surfaces for limiting the movements of said valve means in said hollow piston in response to the fluid pressures applied thereto.

6. In a fluid pressure actuated operator the combination of, a casing having an inlet port and an outlet port, an aperture in said casing, a hollow operator piston slidably disposed in said aperture, fluid responsive valve means carried in said hollow piston for establishing fluid conducting connections to reversely move the hollow piston, fluid conducting ports and passages controlled by the hollow piston for applying fluid pressures to reversely move the valve therein, two interlocking recesses in said valve, an interlocking pin slidably disposed in said piston for engaging at one end with either one of said recesses in said valve, camming surfaces in said casing for engaging the other end of said interlocking pin as the piston moves in the casing to lock the fluid responsive valve in either one of two extreme positions during predetermined movements of the hollow operator piston.

7. In a fluid pressure actuated operator the combination of, a casing, a cylinder bore extending through said casing, an inlet port for receiving working fluid in said casing, an outlet port for discharging exhaust fluid from said casing, fluid conducting passages connecting said ports into said bore, an operator sleeve slidably in said bore, a dumb-bell piston valve slidably disposed in said sleeve for applying fluid pressures to reversely operate said operator sleeve, flow restricting plugs inserted in the ends of said bore and said sleeve, fluid conducting means controlled by the operator sleeve for applying fluid pressures to reversely move the valve therein, two interlocking recesses in said valve, an interlocking pin slidably disposed in the side wall of said operator sleeve for engaging at one end in either one of said recesses, camming surfaces in the side wall of said bore for engaging the other end of said interlocking pin as the operator sleeve slides to either end of the bore to lock the fluid responsive valve in either one of two extreme positions during predetermined movements of the operator sleeve.
8. In a fluid pressure actuated operator the combination of, a casing, a fluid pressure responsive operator piston slidably disposed therein, a fluid responsive valve for applying fluid pressures to reversely move said operator piston, a driven valve for applying fluid pressures to reversely move said fluid responsive valve, slack motion driving means interconnected between said operator piston and said driven valve, and locking means for locking the fluid responsive valve while the driven valve is moving.
9. In a fluid pressure actuated operator the combination of, a casing, a fluid pressure responsive operator piston slidably disposed therein, a fluid responsive valve for applying fluid pressures to reversely move said operator piston, a driven valve for applying fluid pressures to reversely move said fluid responsive valve, means for driving said driven valve comprising a slack motion connection, two locking recesses in said fluid responsive valve, two camming recesses in said driven valve, and a locking pin slidably disposed in said casing for selective operative engagement by said camming recesses at one end and for selectively engaging into either one of said locking recesses at the other end whereby simultaneous movement of the fluid responsive valve and the driven valve is eliminated.
10. In a hydraulic operator for use in uniflow fluid pressure systems the combination of, a casing having an inlet port and an outlet port, a fluid pressure responsive operator member disposed in said casing for movement in response to fluid pressure supplied through said inlet port, fluid responsive valve means movable in said casing for controlling the application of pressure fluid from the inlet port to reversely move the operator member, means controlled by the movements of said operator member for applying fluid pressure to reversely move said fluid responsive valve means, and locking means controlled in accordance with the movements of said operator member and said fluid responsive valve means to prevent stoppage on dead center.
11. In a hydraulic operator for use in uniflow fluid pressure systems the combination of, a casing having an inlet port and an outlet port, a hydraulically operated pressure responsive operator member movably disposed in said casing, a pressure responsive valve for controlling the application of incompressible pressure fluid from the inlet port to reversely move said operator member, fluid flow controlling means controlled by the movements of said operator member for applying unexpansible fluid pressure from the inlet port to reversely move said pressure responsive valve, two spaced locking recesses in said pressure responsive valve, a locking pin slidably disposed for engaging said locking recesses selectively for holding said valve in either one of two extreme positions, and camming means for actuating said pin to lock said valve during a portion of the movement of said operator member.
12. In a hydraulic operator for use in uniflow fluid pressure systems the combination of, a casing having an inlet port and an outlet port, a hydraulically operated pressure responsive operator piston slidably disposed in said casing, a piston valve of the dumb-bell type, a guide bore for slidably supporting said valve, fluid conducting passages controlled by said valve for controlling the application of incompressible pressure fluid from the inlet port to reversely move said operator member, fluid flow controlling means controlled by the movements of said operator member for applying unexpansible fluid pressure from the inlet port to reversely move said pressure responsive valve, two axially spaced locking recesses in said pressure responsive valve, a locking pin slidably disposed for engaging said locking recesses selectively for holding said valve in either one of two extreme positions, and camming means for actuating said pin to lock said valve during a portion of the movement of said operator member.
13. In a fluid pressure actuated operator the combination of, a casing having an inlet port and an outlet port, a fluid pressure responsive operator piston, a bore in said casing for slidably receiving said piston, a first dumb-bell type piston valve, a second dumb-bell type piston valve, bores in said casing of suitable diameter for slidably receiving said valves therein, fluid conducting ports controlled by the first valve for applying fluid pressures from the inlet port to reversely operate said operator piston, fluid conducting ports controlled by the second valve for applying fluid pressures to reversely operate the first valve, a slack motion mechanism for driving said second valve from the operator piston, a pair of locking apertures axially spaced on the first mentioned valve, camming surfaces axially spaced on the second valve, a locking pin, an aperture in said casing for slidably receiving said pin and so arranged that one end of the pin is selectively engaged by the camming surfaces for causing the other end of the pin to selectively engage the spaced locking apertures for locking the first valve in either one of its extreme positions during movement of the second valve.

DAVID R. HILLIS.
